TEMPERATURE COMPENSATED SWITCH

Elihu Craig Thomson, Boston, Mass., assignor to
Combustion Control Corporation, Cambridge,
Mass., a corporation of Massachusetts

Application January 13, 1944, Serial No. 518,130

3 Claims. (Cl. 200—122)

1

This invention relates to electric switches and particularly to switches which are controlled or otherwise affected by temperature-responsive apparatus.

Switches incorporating contact springs which are moved into circuit making or breaking position by actuating elements depend for positive and certain operation upon definite correlation of switch spring position and actuator deflection, especially if one actuator is supposed to operate several contact springs in a given sequence. While it is possible definitely to correlate the switch operation to a given actuator deflection, the latter itself may depend not only upon the controlling effect purposely applied thereto but also upon the ambient temperature which, under unfavorable conditions may even cause undesired switch operation without intended deflection of the actuator. This undesirable effect is especially apt to occur when the actuator is purposely designed to deflect in response to temperature changes applied thereto by a heating element since such actuators will respond to changes of ambient temperature just as much as to the intended temperature changes of the heating element.

It is one of the principal objects of the present invention to provide a switch actuated by a device whose deflection depends on its temperature, and the operation of which switch is independent of ambient temperature conditions. Other objects are to provide a switch of the type described in Patent No. 2,358,372, dated September 19, 1944, which operates reliably, in response to a certain temperature change applied by a heating element, regardless of ambient temperature conditions; to provide a thermally operated switch having two switch elements which establish contact consecutively in predetermined sequence regardless of ambient temperature conditions; and generally to provide a switch of this type which is simple, rugged, inexpensive and yet very accurate and reliable in operation.

In accordance with the invention, actuating as well as contact-making and, if desired, stopping elements of the switch are made of thermoresponsive material and so shaped, arranged and mounted that temperature changes effective with regard to all these elements leave their mechanically effective relative arrangement unaffected although the spatial situation of the group as a whole may change.

These and other objects and aspects will be more fully apparent from the following description of several practical embodiments illustrat-

2

ing the genus of the invention. The description refers to a drawing in which

Figs. 1 to 3 are elevations of a switch according to the invention, with the actuator, contact, and stop elements in various operative positions;

Fig. 4 is a detail view of a bimetallic switch spring according to the invention, and

Fig. 5 a fragmentary elevation of a second embodiment of the invention.

Referring to Figs. 1 to 3, a suitable housing or frame, for example a U-shaped strip 1 (which may have an insulating portion 1a), having tapped holes 2, 3 for mounting the switch on an appropriate support 4, holds between its arms by means of screw bolts 5, 6 a series of blocks 7 and a block 8 of insulating material. Between these blocks and insulated from the bolts are clamped switch spring strips 15, 16, 17, 18 constituting switch contact elements, and an actuating switch strip 19. Screwed to end block 8 is a bimetallic actuator strip 22 which can move only in a plane normal to the plane in which strips 15 to 19 are operating.

Strips 19 and 22 are provided with heating resistors C and D, respectively. In normal, unheated condition, these thermal strips 19, 22 assume the positions shown in Fig. 1, whereas when heated they bend as indicated in Figs. 2 and 3. Suitable means may be provided for adjusting the movement of the thermal strips 19 and 22.

Stops 25, 26 may be provided in order to limit the movement of springs 17, 18 when they follow flexure of actuator 19 towards the right-hand side of the figures, assuring sudden breaking and closing of contact at points C1 and C2, with springs 17, 18, 19 at a definitely predetermined relative position.

The actuating contact strip 19, the contact springs 17 and 18 and stops 25, 26 are made of bimetallic material for the purpose to be described below.

The free ends of switch springs 17, 18 are bent over and downwardly in inverted U-shape with the more distant spring 17 reaching with lateral portion 17a over the similar portion 18a of spring 18, and the descending portions 17b and 18b being arranged to contact spring 19 in unheated position.

The switch springs 15 to 19 are provided with contact points constituting switches C1, C2 and D2; under normal conditions, with bimetal strips 19 and 22 unheated, strip 19 retains contacts C1 and C2 closed (Fig. 1) and insulating finger 24 of strip 22, constituting a stop element, closes switch D2. The lower ends of the switch springs are ex-

tended into tails for connection with lead wires, as indicated at 31.

A resetting mechanism may consist of a cylindrical block or bar 30 of insulating material which has two control faces or shoulders 51, 52 and slides in two openings 53, 54 of frame 1. Opening 53 is wide enough to permit insertion of block 30, but screw 55, if placed as indicated in Figs. 1 to 3, after insertion of the block 30 retains the latter in the frame without, however, hindering its sliding movement in openings 53, 54. A spring 56 inserted between frame 1 and shoulder 51 of block 30 urges the block out of contact with springs 15, 16.

The control faces 51, 52 are preferably so spaced that their distance is greater than the distance of the stop faces of switch springs 15, 16 in open position. Therefore, pushing in of block 30 by means of resetting push button extension 50 will not close switch D, whereas release of the button will permit such closing, if the actuator 22 is in the position indicated in Figs. 1 and 3; with element 22 in the position of Fig. 2, switch D2 is open with spring 15 retaining actuator 22 in deflected position.

The heater coils C and D may be supplied with current through tailed lead strips 61, 62, 63 and insulated connectors 64, 65.

As mentioned before, and shown in Fig. 1, all three switches C1, C2, D2 are closed when the thermal strips 19, 22 are cold. When strip 19 deflects, switches C1 and C2 are permitted to open, with switch C1 opening first as shown in Fig. 3, and switch C2 opening thereafter as shown in Fig. 2. If resistor D heats strip 22, the latter bends laterally (forward in Figs. 1 to 3) and permits switch D2 to open as likewise shown in Fig. 2. Flexure back into the position shown in Fig. 1 will cause reclosing of switches C1 and C2, the contacts being so arranged that switch C2 closes before switch C1.

The operation of switch elements 22, 16, 15 is explained in detail in the above-mentioned patents and not described in detail herein since this aspect of the switch is not part of the present invention and merely shown as belonging to the switch unit chosen for description by way of a well-tested embodiment of the invention.

Switches of the above-described type operate as follows.

When heater C does not carry current, actuator spring 19 contacts springs 17 and 18 and establishes contact at C1 and C2. Bimetallic springs 17 and 18 are so mounted and dimensioned that, with changing temperature, they deflect in the same sense as actuator 19, so that contact at C1, C2, and the general mechanically effective relative location of the three elements is maintained regardless of prevailing ambient temperature.

When current is for control purposes supplied to heater C, actuator strip 19 begins to bend away from strips 17 and 18 which follow the actuator, retaining C1 and C2 closed, until strip 17 strikes stop 25 whereupon C1 opens as shown in Fig. 3. As actuator 19 deflects further, strip 18 strikes stop 26 and C2 also opens.

The effective positions of bimetal stops 25 and 26 likewise change with temperature so that, with proper arrangement which of course depends upon the particular shape and dimension of every individual switch design, the mechanically effective position of contact springs such as 17 and 18, and stop elements such as 25 and 26 can be rendered independent of ambient temperature.

When heater C is disconnected from current supply, actuator 19 deflects in opposite direction, first contacting spring 18 at C2 (Fig. 3) and then spring 17 at C1 (Fig. 1).

It should be noted that the construction shown in Figs. 1 to 3 is especially advantageous to secure opening of one contact, as at C1, before that of another, as C2, for the following reason. Bimetal spring 17 which is to open contact first at C1, is located furthest from heater element C, so that any possible heat transfer from C to 17 is less than from C to 18. Hence, deflection due to such transfer, of 17 and 25 towards 18 is less than of 18 and 26 towards 19, which insures that the tendency of C1 to open first is enhanced rather than diminished, due to the expedient of extending the contact point 17b effective for switching at C1, over contact point 18b effective with regard to switch C2 that depends for operation upon the strip nearer to heater C and is required to open after switch C1.

The principle of the invention can be applied to different switch constructions as for example that of the above-identified patent shown in Fig. 5. In this figure, 1 is the supporting frame, 117, 118 and 119 three bimetallic springs forming switch contacts C1 and C2, and 21 a non-conducting actuator strip carrying an insulating button 23 and a heater element C. The strips 117, 118, 119 and 21 are so arranged that they deflect in the same sense with varying temperature, so that their mechanically effective relative position is not affected by changes in ambient temperature, in the manner described above. Deflection of 21 towards the right of Fig. 5, upon heating by means of coil C, will cause opening of C1 and C2, if desired in a predetermined sequence, and deflection of 21 in opposite direction will analogously cause closing of C1 and C2.

It will be understood that, although advantageously applicable to switches with temperature sensitive elements actuated by any desirable means, the principle of the invention is especially advantageous if one of these elements is purposely made temperature responsive and provided with controlling heater means, as herein described.

It should be understood that the present disclosure is for the purpose of illustration only and that this invention includes all modifications and equivalents which fall within the scope of the appended claims.

I claim:

1. A switch system comprising a switch base, an actuating element adapted to deflect with changing temperature mounted on said base, means for deflecting said actuating element, a switch spring element tending to contact said actuating element, and a stop element limiting said tendency of said switch spring, said switch spring and said stop element being likewise adapted to deflect with changing temperature, and said actuator element and said switch spring being so arranged and mounted on said base that flexure of said actuating element may cause mechanical actuation of said switch element whereas temperature changes of actuating element, switch element and stop element leave the mechanically effective relative location thereof substantially unaffected.

2. A switch system comprising a switch base, an actuating switch element adapted to deflect with changing temperature mounted on said base, means for heating said switch element, a first switch spring element and a second switch spring element likewise adapted to deflect with changing

temperature, said switch elements being so arranged and mounted on said base that flexure of said actuating switch element through temperature change of said heating means may cause contact of said actuating switch element first with one of said switch spring element and thereafter with the other switch spring element through mechanical contact therewith whereas temperature changes of actuating and both switch spring elements leave the mechanically effective relative location of the three elements substantially unaffected.

3. A switch system comprising a switch base, an actuating bimetallic switch strip mounted on said base, a heating coil wound on said switch strip, a first bimetallic switch spring strip and a second bimetallic switch spring strip, said strips being mounted on said base for coplanar deflection with said second spring strip arranged between said actuating strip and said first spring strip, the ends of said spring strips forming contacts extending towards the end of said actuating strip so that flexure of said actuating strip through temperature changes of said coil may cause disengagement of said end of said actuat-

ing strip first from said first spring strip and then from said second spring strip, whereas temperature changes of actuating and both spring strips leave the mechanically effective relative location of the three strips substantially unaffected, and more pronounced heating of said second spring strip from said coil promotes the tendency of said second spring strip to disengage after said first spring strip.
